UNITED STATES PATENT OFFICE.

CHARLES HELLER, OF ANNAPOLIS, MARYLAND, ASSIGNOR OF ONE-HALF
TO JOHN R. STRANGE, OF SAME PLACE.

TABLE ATTACHMENT.

SPECIFICATION forming part of Letters Patent No. 595,476, dated December 14, 1897.

Application filed April 8, 1897. Serial No. 631,293. (No model.)

To all whom it may concern:

Be it known that I, CHARLES HELLER, a citizen of the United States, residing at Annapolis, in the county of Anne Arundel and State 5 of Maryland, have invented certain new and useful Improvements in Table Attachments; and I do hereby declare the following to be a full, clear, and exact description of the invention, such as will enable others skilled in the 10 art to which it appertains to make and use the same.

My invention relates to improvements in table attachments, and has more particularly for its object to provide means whereby the 15 chairs used in connection with a dining-table, writing-table, or the like may be conveniently and easily stored out of the way beneath the table when not in use.

My invention is especially adapted for use 20 on board ship, in hotel dining-rooms, and writing-rooms; and it also contemplates the provision of a special form of folding chair to be used with such an attachment to a table.

My invention will be understood by reference 25 to the accompanying drawings, wherein the same parts are indicated by the same letters throughout the several views.

Figure 1 represents an inverted plan view 30 of a portion of a table provided with three of my attachments and shows a chair as held in position by one of such attachments. Fig. 2 is a partial sectional view taken on the line 2 2 of Fig. 1 and looking in the direction of the arrows. Fig. 3 is a side elevation of the 35 chair shown folded and stored beneath the table in Figs. 1 and 2 as it appears when in position for use. Fig. 4 represents a rear elevation of the chair shown in Fig. 3; and Fig. 5 represents a side elevation of the chair shown 40 in Figs. 3 and 4, having its back detached from the seat and folded down in position to allow the chair to be stored beneath the table. Fig. 6 represents a perspective view of the improved socket-plate with the table-leg therein.

45 In Fig. 1, A represents the table-top, A' A' represent the legs, and A² A² represent the sills or side pieces.

The table-legs are secured in the socket-pieces A⁰, having slotted lugs a⁰ to receive the 50 sills or side pieces A². These socket-pieces

are preferably made rectangular or square to hold the leg firmly, and the socket for the table is made sloping, so as to receive the leg, which is put in place before the socket-plate is attached to the table. The top of the leg 55 comes flush with the top of the socket-plate, and the whole may be detachably connected by screws or in any other convenient way.

To the under side of the top A a plurality of brackets B, each having a pair of perforated lugs b b, are attached by means of screws or bolts passing through said lugs and entering the table-top. Each of these brackets B is braced upon its inner side by means of a leg or brace B', rigidly fixed at one end to said 60 bracket and at the other end provided with a perforated lug b', which is rigidly secured to the under side of the table-top by means of screws, as seen in Figs. 1 and 2. A frame or arm B², which is preferably composed of a 65 metallic rod bent to form a pair of legs, as shown in Fig. 1, is pivoted at one end in a pair of straps or cleats b² b² on the bracket B, the end of each of the legs of this frame being bent at right angles to the leg itself and sprung 70 into the said straps or cleats, as will be obvious from an inspection of Fig. 1. The length of this frame B², and consequently the distance from the side pieces of the table to the point of attachment of the bracket B, 75 should be somewhat greater than the width of the chair-seat from front to back, so that when the chair is folded, as in Fig. 5, it may be suspended upon the arm or frame B² between the side piece of the table and the 80 bracket B, as shown in Figs. 1 and 2. In order that this frame B² may be held in a horizontal position when not in use, and also in order that it may be caused to support the 85 chair, I provide a bent metallic spring-arm bracket B³, which is provided at one end with a foot b³, adapted to engage in a cleat or strap b⁴ on the bracket B and form a rigid support for the said spring, and which is provided at its 90 opposite end with a pair of laterally-extending arms b⁵ b⁵, which bear against the under side of the legs of the frame B² and thus support said frame in a horizontal position. It 95 will be seen, however, that the resiliency of the spring-arm B³ will allow the frame B² to 100

be turned down sufficiently to insert or withdraw the chair.

The special form of chair designed by me for use with the above-described table attachment is shown most clearly in Figs. 3, 4, and 5, and comprises the following essential elements:

The seat C' of the chair C should be comparatively flat, but may be of any ordinary suitable construction. The back C² may also be of any suitable construction, but should have an opening of some sort, such as C⁰, at or near the top thereof, to allow the passage of the holding arm or frame B² on the table. 15 This back C² is hinged to the seat by means of side pieces, such as C³ C³, pivoted to the seat and the back, as shown in Figs. 3, 4, and 5, so that the said back may swing downward when released until its top is level with or 20 below the top of the seat, as seen in Fig. 5.

The bottom of the back of the chair is provided with one or more tenons c², which is adapted to fit into a mortise c' in the rear of the seat of the chair when the back is raised. 25 The back may be locked in this position, so as to allow the chair to be carried about by the back and used by means of a spring-catch c³ on the lower end of the said back adapted to engage a stud c⁴ on the rear of the seat, as 30 seen in Figs. 3 and 4.

When it is desired to fold the chair, it is simply necessary to release this catch c³ from the stud c⁴, and the back may be disengaged from the seat and swung downward, as above 35 described.

In storing the chair beneath the table the chair is first folded, as shown in Fig. 5, and then the forward edge of the seat is inserted between the top of the table and the 40 outer end of the frame B². By bearing down slightly upon the chair the frame may be depressed and the chair simultaneously slid inward above the frame B² until the rear edge of the chair passes the inner side of the side 45 piece A² of the table, when it is released, and the action of the spring B³ will hold the frame B² and the chair C firmly up against the under side of the table-top, as shown in Fig. 5. The outer end of the frame B² will project 50 through the opening in the back of the chair and also slightly beyond the outer side of the side piece A², so that it may be readily depressed when the chair is to be withdrawn.

It will be obvious that I may use simply a 55 coil-spring in place of the bent spring B³, if preferred, especially where light chairs are to be used.

Instead of the spring B³, having arms b⁵, as shown, it will be obvious that two single springs may be used, one to support each arm 60 of the frame B².

Although I have described and shown a particular form of chair to be used with my table attachment, I do not wish to limit myself to any particular form of chair, as many 65 forms now in use could be readily adapted to the said attachment without departing from the spirit of my invention.

Having thus described my invention, what I claim, and desire to secure by Letters Patent of the United States, is—

1. The combination with a table, of a plurality of depending brackets mounted upon the under side of the top thereof; a bent metallic rod pivoted upon each of said brackets; 75 and a bent metallic spring also mounted upon each of said brackets, and pressing said bent rods upward, substantially as described.

2. In a table attachment of the character described, the combination with a metallic 80 bracket, and means for securing said bracket to the under side of the table-top; of a frame pivoted upon said bracket; and a bent metallic spring fixed at one end upon said bracket, and at the opposite end adapted to bear upon 85 said pivoted frame, as and for the purposes described.

3. In a table attachment of the character described, the combination with a bracket provided upon its base with lugs for the passage of screws; a brace fixed upon one side 90 of said bracket; a frame comprising two parallel arms pivoted upon said bracket; and a bent metallic spring fixed at one end upon said bracket, and at the opposite end adapted 95 to bear upon said frame, substantially as and for the purposes described.

4. In a table attachment of the character described, the combination with a bracket provided with means for attaching said 100 bracket to the table, and having a pair of cleats thereon; of a frame comprising a bent metallic rod having two parallel legs pivoted in said cleats; and a spring fixed upon said bracket and adapted to bear upon said legs, 105 substantially as and for the purposes described.

In testimony whereof I affix my signature in presence of two witnesses.

CHARLES HELLER.

Witnesses:

CHARLES G. FELDMAYER,
JOHN R. STRANGE.
